UNITED STATES PATENT OFFICE.

HARRY C. FRATT, OF NORRISTOWN, PENNSYLVANIA.

ICE-PAN FOR REFRIGERATORS.

1,286,575.

Specification of Letters Patent.

Patented Dec. 3, 1918.

Application filed August 22, 1916. Serial No. 116,334.

To all whom it may concern:

Be it known that I, HARRY C. FRATT, a citizen of the United States, residing at Norristown, in the county of Montgomery and State of Pennsylvania, have invented new and useful Improvements in Ice-Pans for Refrigerators, of which the following is a specification.

This invention relates to refrigerators and 10 has particular application to a pan for supporting the ice within the ice compartment of a refrigerator.

The chief characteristic of this invention is to provide a device of this character which 15 will support the ice within the refrigerator in such a manner as to permit the free circulation of air about the ice whereby the maximum amount of cooling effect will be obtained.

20 Another characteristic of this invention resides in the provision of a device of the above described character having novel means of supporting the pan within the refrigerator to permit the ready removal of 25 the same.

Another characteristic of this invention is to provide a device of this character having an auxiliary drain pan which is arranged in 30 baffled relation to the ice pan whereby the water from the ice can be subjected to a prolonged exposure to permit the air within the ice chamber to evaporate the water from the ice.

Another object of this invention is to provide 35 novel means for supporting the drain pan whereby the same may be readily removed for cleaning purposes.

Another object of this invention is to provide 40 a device of this character which contains the desirable features of simplicity, durability and efficiency and furthermore, a device which may be readily attached to a refrigerator of any common construction.

Other objects of the invention will appear 45 as the specification is read in connection with the accompanying drawings, in which:—

Figure 1 is a top plan view of a device 50 constructed in accordance with my invention, the refrigerator being shown partly in section.

Fig. 2 is a vertical longitudinal section of the device, the refrigerator being shown in section.

Fig. 3 is a perspective view of the ice pan. 55 Fig. 4 is a transverse section of the same.

Fig. 5 is a perspective view of the auxiliary drain' pan.

Fig. 6 is a transverse section of the ice chamber of the refrigerator showing a portion of the means for supporting the pans 60 within the ice chamber.

Referring to the drawings in detail, my invention is shown in this instance applied to an ice chamber of a refrigerator, the ice chamber being generally indicated as at A 65 and preferably of rectangular formation and comprising side walls 1, and end walls 2. Secured to the confronting faces of the end walls 2 by means of the screws 3, at a point adjacent the lower edge of the chamber, is a plate 4 which extends transversely of the end walls and has its lower longitudinal edges bent inwardly at right angles to provide the flanges 5, the opposite ends of the flanges being upturned as at 6. The 70 flanges upon one of the plates 4 and preferably the rear plate is disposed in a plane below the flange formed on the forward plate, the purpose of which will be herein-after described.

80 Removably mounted between the flanges 5 is the drain pan 7 which is formed from a single piece of metal which is preferably of rectangular formation. The pan 7 is bent longitudinally in the form of a syncline and 85 has one end thereof provided with an upturned flange 8 while, adjacent the flange at the medial portion of the pan is an opening 9, to the walls of which is secured a depending pipe 10. The opposite longitudinal 90 edges are bent downwardly and inwardly upon themselves to provide the annular channels 11 in which are mounted the rods 12. The rods 12 are of such a length as to project beyond the opposite ends of the 95 channels and serve as supporting means for the pan, the ends of the rods lying upon the flanges 5 when the pan is in applied position within the ice chamber.

100 It will be noted that owing to the fact that the flanges 5 are disposed in different horizontal planes, when the pan 7 is in applied position, the same will be disposed upon an incline, from its forward end to its rear end, thus causing the liquid which is deposited 105 upon the pan to be precipitated toward and through the drain opening 9.

Secured to the confronting faces of the end walls 2 at points above the plates 4 are the transversely extending bars 13, the bars 110

being preferably secured at suitable points by means of screws 14. The upper longitudinal edges of the bars 13 are provided with recesses 15 adjacent the opposite ends thereof, the recesses upon the rear bar being in horizontal alinement with the recesses upon the remaining bar.

Mounted upon the bars 15 and connecting the same is my improved form of an ice pan 16 which comprises a sheet of metal bent upwardly upon its marginal edges to provide the side walls 17 and the end walls 18, the walls being rigidly connected together by solder or the like. The ice pan is bent longitudinally at its medial portion in the form of a syncline and is provided adjacent one end with a drain opening 19, the latter having secured to its wall, the depending pipe 20. The bottom of the pan is deeper at one end than at the other, the bottom being inclined toward the drain opening 19. The side walls 17 have their longitudinal free edges bent outwardly and downwardly to provide channels 21 in which are mounted the upper edge of the longitudinally extending strips 22. The strips 22 are secured to the side walls 17 by means of the rivets 23, the strips being of such a length as to project beyond the opposite ends of the ice pan and terminating in rabbeted portions to provide the projections 24. When the ice pan 16 is in applied position within the ice chamber, these projections 24 are adapted to lie within the recesses 15, the bar 13 being so disposed as to normally hold the ice pan in spaced relation to the drain pan 7. It will be noted that the ice pan is so disposed within the ice chamber as to have the drain opening 19 disposed at the forward end of the casing, while the opening 9 formed in the drain pan 7 is disposed at the rear end of the chamber as has been described.

To support the ice upon the pan and at the same time to permit the free circulation of air about the ice, an ice tray 25 is mounted upon the ice pan 16 and between the side and end walls thereof. The ice tray 25 is in this instance formed of horizontally extending bars 26 which are connected by the parallel spaced longitudinally extending bars 27.

In operation, the pans 7 and 16 are placed within the ice chamber as has been described, the ice being placed upon the tray 25. As the ice melts, the water will fall upon the pan 16 and owing to its synclined and inclined formation, the water will be precipitated toward the drain opening 19 and through the pipe 20 and to the drain pan 7. The water then traverses the pan 7 and through the opening 9 and pipe 10. A suit-

able drain pipe may be connected to the pipe 10 for directing the water into a drip pan as will be understood. It will be evident from the foregoing that owing to the arrangement of the pan, the water will be subjected to a prolonged exposure thereby permitting the air within the chamber to evaporate the water, thus lowering the temperature of the air and assisting the ice in cooling the contents of the refrigerator. It will be noted that the pans 7 and 16 are of a less width than that of the chamber thereby permitting the air to freely circulate about the pan and ice. In the event that it is desired to clean the pans, they may be readily removed and easily replaced as will be understood.

Supporting means for the pan including the plates 4 and the bars 13 are secured to the end walls of the chamber by means of the screws as has been described. Thus it will be manifest that the supporting means may be readily applied to the ice chamber and a refrigerator for supporting the pans in their proper coöperative positions.

It is thought from the foregoing taken in connection with the accompanying drawings, that the construction and operation of my device will be apparent to those skilled in the art, without further description, and that minor changes in size, shape, proportion and minor details of construction may be made without departing from the spirit and scope of the appended claim.

What I claim is:

In a refrigerator, a pair of cleats disposed upon the inner faces of the end walls of the ice chamber at the lower edges thereof, said cleats being provided with inturned flanges and one cleat extending below the lower edge of the associated end wall, a pan disposed below said ice chamber and having its sides provided with rods projecting beyond the ends thereof and engaging upon the inturned flanges of said cleats whereby said pan will be supported with one end lower than the other, a second pair of cleats secured upon the inner sides of said end walls above and in spaced relation to said first named cleats and provided with notches, and an ice supporting pan disposed above said first named pan and having its ends provided with projections seating within said notches, the bottom of said second named pan being inclined and having its lowest point disposed adjacent the highest point of the bottom of said first named pan, and the lowermost point of each pan being provided with an outlet opening.

In testimony whereof I affix my signature.

HARRY C. FRATT.
